(57) **CLAIM**

The ornamental design for a light fixture, as shown and described.

DESCRIPTION

FIG. 1 is a perspective view of a light fixture in accordance with my design;

FIG. 2 is a top plan view of the light fixture in accordance with my design;

FIG. 3 is a bottom plan view of the light fixture in accordance with my design; and,

FIG. 4 is a front elevation view of the light fixture in accordance with my design, all elevation views being substantially identical.

The portions of the light fixture shown broken away in FIGS. 1–4 are to depict nonspecific length.

The broken-line disclosure of elements is understood to represent portions of the article in which the design is embodied, but which form no part of the claimed design.
